BRUSH CONTAINER

Frank Lieberman, Detroit, Mich.

Application January 3, 1949, Serial No. 68,870

1 Claim. (Cl. 206—15.1)

1

This invention relates to a paint brush container, and more particularly to the construction of a paint brush pocket or supporting member which is adapted to supportably receive a paint brush, with said pocket member being adapted for positioning upon and within a box or other container containing a brush cleaning fluid.

It is the object of the present invention to provide a paint brush supporting pocket member which consists of a pair of oppositely arranged hingedly joined pocket elements for completely enclosing the paint brush and being adapted to support the same upon and within a box containing a brush cleaning fluid.

It is the further object of the present invention to provide a very efficient paint brush container for safely storing paint brushes and at the same time preventing physical damage to the delicate bristles.

It is the further object of the present invention to provide a paint brush supporting member which protectively encloses the paint brush and which includes a supporting clip upon the interior thereof for retaining the paint brush therein so that the weight thereof is not upon the bristles.

It is the further object of this invention to provide in said supporting pocket member a clip or other formation which is pressed from a portion of one of the pocket elements and which extends in parallel spaced relation to the other surface thereof for cooperative supporting engagement upon the peripheral edge of a cleaning fluid container, or upon any supporting wire, as for instance the supporting wire forming a part of a wire cage positioned within said fluid container.

It is the still further object of the present invention to provide a novel paint brush supporting pocket, the lower portions of which are inwardly inclined to provide a wedge shape corresponding to the shape of the brush stored, with the lower ends of the side walls of said pocket elements being hingedly joined together and with the top walls thereof being formed with suitable clips for securing said pockets in closed position.

These and many other objects will be seen from the following specification and claim in conjunction with the appended drawing in which:

Figure 1 is a perspective view of a rectangularly shaped container with brush supporting pockets suspended thereon.

Figure 2 is a perspective view of a slightly different shape of container with said brush supporting pockets shown suspended from a wire cage, which in the drawing is shown as suspended

2

directly above said container and which is adapted to be dropped therein.

Figure 3 is a perspective view of a brush supporting pocket member which is opened to illustrate the positioning of the brush therein.

Figure 4 is a perspective view of the wire cage shown in Figure 2.

Figure 5 is a front elevational view of the pocket member when closed.

Figure 6 is a right side elevational view thereof.

Figure 7 is an elevational section taken on line 7—7 of Figure 5; and

Figure 8 is a top plan view of said pocket member.

It will be understood that the above drawing illustrates merely a preferred embodiment of the invention and that other embodiments are contemplated within the scope of the claims hereinafter set out.

Referring to the drawing one form of hollow rectangularly shaped container 11 is shown in Figure 1, said container being adapted to contain a given quantity of brush cleaning fluid, and having supporting handles 12.

In Figure 1 the brush containing and supporting pocket members are supported within container 11 in the manner hereafter described, whereas in Figure 2 there is shown hollow container 13 with hinged cover 14 which is adapted to receive and support pocket holding cage 15, the detail of which is shown in Figure 4.

The cage 15 hereafter described in detail is provided with a suitable handle 16 whereby the same may be inserted and removed from container 13 as and when desired.

The brush enclosing and supporting pockets 17, Figures 3, 5, 6, 7 and 8 consist of the pair of identical pocket elements 18 and 19, the lower ends of whose side wall portions are pivotally joined to each other as by the rivets 20.

Said elements have side walls 18' and 19' respectively as well as top wall portions 24, however, the hollow pockets or pocket elements 18 and 19 are open at their lower ends to thereby provide a rectangular opening 21 when said lower ends are pivotally joined together as indicated in Figure 7. By this construction it is apparent that the brush bristles 41 will not engage at their ends any portion of the pocket member 17 but will lie within the open space adjacent the rectangular opening 21 at the lower end of said pocket member.

Each of the pocket elements 18 and 19 are identical in shape and are normally arranged oppositely from each other with element 19 positioned

within element 18 in the manner shown in Figures 3, 6 and 7.

Each of said elements include the inwardly inclined surfaces 22 at their lower ends as well as the upright substantially parallel surfaces 23, which terminate in the top walls 24.

Substantially semi-circular recesses 25 are formed in said top walls 24 at central portions thereof to provide a substantially circular or elliptical opening to cooperatively receive a portion 39 of paint brush handle 38.

Referring to Figure 6 it appears that the outer edges 26 of pocket element 18 corresponding to the inclined surfaces 22 slidably overlap the corresponding outer edges and side wall portions 19' of the pocket element 19, providing an effective closure for the lower portion of the brush supporting pocket 17.

However, it is apparent from the drawing that only the lower side wall portions of said wall elements overlap each other when closed inasmuch as the upper portions of said sidewalls terminate in the registering outwardly projecting flanges 27 as shown in Figure 6. Similarly the edges of the top wall portions 24, with the exception of the portion bounding the recesses 25, terminate in the registering upwardly extending flanges 28 Figure 8.

Consequently it is clear that the registering engaging flanges 27 and 28 limit the closing movement of pocket elements 18 and 19, but are so aligned with each other as to provide a complete enclosure for the paint brush to be positioned and supported therein.

Resilient clips 29 project inwardly from opposite ends of the opposed pocket elements 18 and 19, said clips forming a part of the upright flanges 28 and extending therefrom to retainingly and resiliently engage the corresponding opposite top edge of the adjacent flange 28.

As elements 18 and 19 are identical in shape, it is apparent that the said elements are constructed with only one clip 29, so that when said elements are arranged in opposing relation, clip 29 of element 18 retainingly engages upright flange 28 of element 19. Similarly the clip 29 of element 19 retainingly engages the corresponding portion of flange 28 of the opposed pocket element 18. Thus effective means are provided for normally retaining pocket elements 18 and 19 in the closed position shown in Figures 6, 7 and 8, said clips being sufficiently resilient as to permit easy opening of said elements around their pivotal points 28.

A bifurcated brush handle engaging clip 30 is positioned within the upper portion of the pocket 17 being secured centrally to the upper portion of pocket element 19 as by the rivet 31. Clip 30 is sufficiently resilient as to cooperatively and retainingly receive the shank 39 of brush handle 38 so as to effectively support brush 40 and its bristles 41 within said pocket when the pocket elements are closed as in Figure 6.

It is particularly important in the present construction that the resilient clip 30 be so constructed and so arranged as to take the weight of the brush, which is often times considerable, so that the weight of said brush is not supported by the bristles 41.

The average fine horsehair brush is expensive and the bristles are delicate and may be easily damaged, particularly if the weight of the brush is supported upon the bristle tips. Consequently the principal object of the invention is satisfied by the pocket construction which completely en-

closes the brush but which provides the clip 30 for supporting the same therein so that said brush is suspended.

The other pocket element 18 has a punched out portion 32 which is so formed as shown in Figures 6, 7 and 8 as to project from said element in parallel spaced relation and which extends downwardly.

Consequently when the pocket member 17 is closed, the same may be effectively supported within container 11 Figure 1 by projecting the pocket support 32 over the top peripheral edge of the container as indicated.

On the other hand the punched out support 32 may provide a means of suspending the pocket 17 in many different ways such as upon the wire cage 15 shown in Figures 2 and 4, or on the other hand said support may be positioned over any horizontally extending wire if desired.

As shown in Figure 7 the support 32 is formed from the pocket element 18 to leave the rectangularly shaped opening 33 out from which it was cut and formed.

As viewed in Figure 6 the top edges of pocket elements 18 and 19 are rounded as at points 34, and similarly the edges 35 and 37 are rounded to facilitate handling of the pocket. Referring to Figure 5 the connecting flanges 27 and 28 are similarly rounded at points 36 to conform to the shape of the pocket.

Now referring to Figure 4 the wire cage which is positionable within the brush cleaning fluid in container 13, includes the four upright legs 42 and the oppositely arranged inclined portions 43 which cooperate with said legs to form a support for the cage 15 either within container 13 or when said cage is removed therefrom and rested upon any other surface.

As shown in Figure 4 said cage also includes the upper and lower hollow rectangular wire frame elements 44 as well as the parallel spaced interconnecting cross braces 45 and 46, and including the transverse compartment forming cross pieces 47 and 48 which interconnect at their ends spaced portions of parallel elements 45 and 46. By the construction shown in Figure 4 there is provided the 8 brush supporting pocket compartments 49, 50, 51, 52, 53, 54, 55 and 56, within which the brush pockets 17 may be positioned in the manner illustrated in Figure 2.

In each case the pocket supports 32 project over the adjacent wire portion of the wire cage as indicated in Figure 2 so that the respective pockets are retained within the various compartments, all in the manner illustrated, particularly in Figs. 2 and 4.

Having described my invention, reference should now be had to the claim which follows for determining the scope thereof.

I claim:

A paint brush supporting pocket member comprising a pair of hollow oppositely arranged similarly shaped pocket elements pivotally joined together at their lower ends, the lower portions of said elements converging inwardly with the side walls thereof corresponding to said converging portions being arranged in overlapping engaging relation, each of said pocket elements having registering out-turned flanges projecting from the edges of said side walls above said converging portions, the respective top walls also having registering out-turned flanges projecting from the edges thereof, there being registering recesses formed in said top walls to receive a

brush handle, a bifurcated brush handle supporting and securing clip joined to and projecting inwardly from the interior of one of said pocket elements retainingly engageable with the brush handle and oppositely extending resilient clips projecting inwardly from opposite ends of each of said top wall flanges to retainingly engage the adjacent top wall flange of the other wall.
